Patented Nov. 1, 1910.

UNITED STATES PATENT OFFICE.

FRANCIS W. TULLY, OF BROOKLINE, MASSACHUSETTS.

EXHIBITING APPARATUS.

974,450.

Specification of Letters Patent.

Patented Nov. 1, 1910.

Application filed March 11, 1910. Serial No. 548,698.

To all whom it may concern:

Be it known that I, FRANCIS W. TULLY, a citizen of the United States, and resident of Brookline, in the county of Norfolk and State of Massachusetts, have invented new and useful Improvements in Exhibiting Apparatus, of which the following is a specification.

This invention relates to exhibiting apparatus, and particularly to exhibiting apparatus, designed for advertising purposes to demonstrate the amount of wear an article will endure when subjected to sharp percussive blows.

While the invention is susceptible of various embodiments, and is applicable to the testing or exhibiting of the durability of various articles when subjected to percussion, it is chiefly intended for demonstrating the durability of articles of wearing apparel, such as hosiery, and I will therefore, for the purpose of illustration, describe the invention as embodied in an apparatus for testing and advertising hosiery. It will be understood however that the invention is not limited to such specific use.

In the accompanying drawings, which illustrate certain embodiments of the invention,—Figure 1 is a side elevation, partly in section, of an apparatus for exhibiting the durability of hosiery when subjected to the percussive blows of hammers; and Fig. 2 is a similar view of the apparatus showing a different form of operating mechanism.

The working parts of the apparatus are supported by, and contained in the casing or frame A. Mounted on the casing A is a foot form B, which holds the stocking to be tested. The form B may be rigidly and immovably mounted on the casing, but is preferably movably mounted, as by the pivot b, and is held to very slight movement by a pair of opposed springs s, which yield slightly in response to the impact of the hammer and thus ease or cushion the blow to some extent.

At either side of the foot form B are hammers or similar strikers D, D', held by the oppositely arranged, dummy hands and arms E, E', which are pivoted to the case A at e and e' respectively. It will be seen that the relative proportions and arrangements of the parts are such that the hammers when swung on their pivots, travel in paths to strike the toe and heel respectively of the

foot form percussive blows, the paths or directions of the striking blows of the two hammers being substantially opposed to each other. The operating mechanism illustrated in Fig. 1 consists of the reciprocating bar F mounted to slide lengthwise in guideways provided in the supports f, which are secured within the casing A. A motor M, preferably an electric motor, is mounted on the base of the casing, and drives a pulley P by means of a belt p. The pulley P is journaled on bracket p', and is provided with a pitman p² which actuates the reciprocating bar F, through the arm p³. Latches C and C' are mounted in the casing on pivots c and c', each latch adapted to engage a notch e² or e³, provided in a disk or plate e⁴ secured to each arm about the pivot. Latch operating pins f² are secured to the bar F, and the bar F is connected at its ends with the lower ends of the arms E and E' by flexible straps f³ and f⁴, as shown. In the position shown in the drawings the bar F is shifted to its extreme position toward the right.

The operation of the apparatus is as follows: When the motor M and the intervening mechanism by which the bar F is connected with the motor, causes the bar to start from the position shown in the drawings toward the left, the arm E' and hammer D' will be lifted away from the foot form B, by strap f⁴. At the same time the pin f² will move away from the lower lever arm of latch C' leaving the same free to drop into notch e³ when the notch comes opposite the end of the latch. As the bar F approaches its left hand position, the arm E' will be swung upward until latch C' drops into notch e³, holding the arm E' and hammer D' in elevated position, and the left hand pin f² will engage and swing the lower lever arm of latch C, thus throwing the latch out of engagement with notch e² and permitting the arm E and hammer D to fall and strike the toe of the foot form. It will be understood that the strap f³ slackens during the left hand movement of the bar F, since the arm E is held upright until the pin f² trips the latch C, and that the fall of the arm and hammer takes up the slack. The reverse movement of the reciprocating bar F operates as already described, first lifting arm E and hammer D, and then releasing arm E' and hammer D' and resetting arm E and hammer D again in the position shown in

the drawings. So long as the reciprocation of bar F continues the hammers will be caused alternately to strike the foot form.

- It will be seen that the arms E and E' carrying the hammers are pivoted at points sufficiently far removed from the foot form so that their striking blows may be effected by gravity, since their centers of gravity never pass outside of their pivotal centers 5 when the arms are raised to their highest points. Furthermore, when the mechanism shown in Fig. 1 is used, each hammer is lifted out of engagement with the foot form when the other hammer strikes its blow.
- 10 Referring now to the form of operating mechanism shown in Fig. 2, the reciprocating bar F and the means for actuating the same may be as already described; and the disks or plates e⁴ having the notches e² and e³, serving as levers for lifting the arms and hammers, may also be substantially the same as already described, save that the notches are located at the bottoms instead of the sides of the disks. Pivoted to each end of 15 bar F is a yielding latch g, normally held projected as shown, by spring g', a stop g² limiting the extent of the upward movement of the latch. In the position shown in Fig. 2, the bar F is at its extreme right hand position. As the bar F moves toward the left, the right hand latch g engages notch e³ and lifts arm E' and hammer D' away from the foot form B, and the left hand latch g yields until it passes clear of the edge of notch e² 20 and snaps into said notch. Just before bar F reaches its extreme left hand position, notch e³ which has been swung upward by the movement of the bar, slips off the right hand latch g, and releases the arm E' and hammer D', which fall by gravity, and the hammer D' strikes the heel of the foot form a percussive blow. A similar action takes place with respect to the arm and hammer E and D when the bar F moves 25 toward the right; and the hammers D and D' are caused alternately to strike percussive blows upon the toe and heel of the foot form, and consequently upon the stocking held thereby, as the bar reciprocates, affording a conspicuous demonstration of the durability of the article subjected to such repeated percussion.
- 30 In the form shown in Fig. 2 each hammer rests against the foot form when the other hammer strikes its blow, whereas in the form shown in Fig. 1 each hammer is re-

moved from contact with the form when the other hammer strikes its blow.

I claim:

1. In an exhibiting apparatus, a foot 60 form pivotally mounted and held to slight yielding movement by opposed cushion springs, a hammer at each side of said foot form, one hammer pivoted to swing in a path to strike the toe of said form, and the 65 other hammer pivoted to swing in a path to strike the heel of said form, the striking blows of said hammers being directionally opposed to each other, and means to reciprocate said hammers.

70 2. In an exhibiting apparatus, a foot form pivotally mounted and held to slight yielding movement by opposed cushion springs, a hammer at each side of said foot form, one hammer pivoted to swing in a 75 path to strike the toe of said form, and the other hammer pivoted to swing in a path to strike the heel of said form, the striking blows of said hammers being directionally opposed to each other, and means to reciprocate said hammers alternately so as to strike toe and heel alternate percussive blows.

80 3. In an exhibiting apparatus, a foot form pivotally mounted and held to slight yielding movement by opposed cushion 85 springs, a hammer at each side of said foot form, one hammer held by a dummy hand and arm pivoted to swing in a path to strike the toe of said form, and the other hammer held by an oppositely disposed dummy hand 90 and arm pivoted to swing in a path to strike the heel of said form, the striking blows of said hammers being directionally opposed to each other, and means to reciprocate said hammers.

95 4. In an exhibiting apparatus, a form adapted to hold an article of wearing apparel, a hammer at each side of said form pivoted to swing in a path to strike said form, by gravity, means to swing said hammers through their return strokes and to release them at the ends thereof, and means whereby each hammer will be removed from contact with the form when the other hammer strikes the form.

100 Signed by me at Boston, Massachusetts, this 10th day of March, 1910.

FRANCIS W. TULLY.
